Cornelius Bollinger

United States Patent Office.

CORNELIUS BOLLINGER, OF HARRISBURG, PENNSYLVANIA.

Letters Patent No. 78,179, dated May 26, 1868; antedated May 14, 1868.

IMPROVEMENT IN STEAM-ENGINE PISTONS.

The Schedule referred to in these Letters Patent and making part of the same.

TO ALL WHOM IT MAY CONCERN:

Be it known that I, CORNELIUS BOLLINGER, of Harrisburg, Dauphin county, State of Pennsylvania, have invented certain new and useful Improvements in Pistons for Pumps, Steam-Engines, &c.; and I do hereby declare the following description and accompanying drawings are sufficient to enable any person skilled in the art or science to which it most nearly appertains to make and use my said invention or improvements without further invention or experiment.

The nature of my invention and improvements consists in a cone, working through the head of the piston, and screwing into the head, or on to the rod, or both, and acting on the sectors which tighten the packing, to force them out, to tighten the packing when required; and in some lugs on the cone, combined with lugs on the cylinder-head, to hold the cone while the piston is turned to screw in the cone, and tighten the packing.

In the accompanying drawings—

Figure 1 is a plan of the lower end of the piston.

Figure 2 is a plan of the lower side of the piston, with the outer plate and cone removed, to show the sectors and packing.

Figure 3 is an elevation of the piston, and

Figure 4 a section, showing it cut through the centre.

In these drawings, A is a piston-head, firmly fastened to the rod B, which is to traverse the piston, if used in a pump, or to be traversed by the piston, if used in a steam-engine. The head, A, has three lugs, C C C, on it, to hold the lower plate, D, of the piston a given distance from A, to which it is fastened by the screws E E, as shown in fig. 4. The packing F may be made of a series of rings, of metal, leather, or India rubber, and pressed out against the cylinder by the sectors G G, of which there may be a proper or convenient number, according to the size of the piston. These sectors G are made with openings in them, for the lugs C and screws E, shown in section, and the lugs and openings in fig. 2. To force out the sectors, I make a cylindrical nut, H, with a conical end, as shown in fig. 4, with a female screw in it, fitted to a male screw on the piston-rod, and a male screw on the outside of the nut, fitted to a female screw in the lower plate, D, all as shown in fig. 4. The corners of the sectors G are countersunk or bevelled off, to correspond with the conical end of the nut H, so that, as the nut is screwed in by the lugs I I, the sectors are forced out by the cone, to tighten the packing against the cylinder; and the packing may be tightened without taking off either cylinder-head, if the cylinder-head next to the screw H is provided with lugs on the inside corresponding with the lugs I I on the nut H, so that the link of the piston-rod can be unhooked from the crank, and the nut pushed against the cylinder-head, and the piston turned by the link, to screw in nut H, which will be held from turning by the lugs on the cylinder-head.

Figure 5 shows a plan of the lugs K K, which may be cast on the cylinder-head, to prevent the nut H from turning when the piston is turned; or, the lugs may be made in a separate block, as shown in Figure 6, and fastened to the cylinder-head.

The nut H may be made with a screw-thread on the inside only, or on the outside only, if preferred that way.

In combination with the piston-head A, fastened to the piston-rod, I claim—

The conical nut H, constructed with a female screw on the inside, to fit the piston-rod, and a male screw on the outside, to fit the piston-head, in combination with the piston-head and rod, as described.

In combination with the conical nut H, provided with lugs I I, I claim the corresponding lugs on the head of the cylinder.

CORNELIUS BOLLINGER.
